[57] CLAIM

The ornamental design for "Bezel Ring for Analog Wristwatch", as shown and described.

DESCRIPTION

FIG. 1 is a top plan view of my improved bezel ring for an analog wristwatch;

FIG. 2 is a right side elevational view thereof;

FIG. 3 is a left side elevational view thereof;

FIG. 4 is a front end elevational view thereof;

FIG. 5 is a rear end elevational view thereof; and

FIG. 6 is a bottom plan view thereof.

The watchcase and strap, portions of which are shown in dashed and phantom lines in FIG. 1, are not part of the design.

The broken line showing of a watchcase and band portions are environmental only and form no part of the claimed design.
